UNITED STATES PATENT OFFICE.

CHARLES SPIRO, OF NEW YORK, N. Y.

INKING DEVICE FOR TYPE-WRITING MACHINES.

SPECIFICATION forming part of Letters Patent No. 355,418, dated January 4, 1887.

Application filed May 1, 1885. Serial No. 164,072. (No model.)

To all whom it may concern:

Be it known that I, CHARLES SPIRO, a citizen of the United States, residing at New York, in the county of New York and State of New York, have invented certain new and useful Improvements in Inking Devices for Type-Writers, of which the following is a specification, reference being had to the accompanying drawings.

10 This invention has relation to inking devices for type-writers, and has for its object the simplification of the devices for receiving and presenting in operative position the inking devices employed.

15 Other objects and advantages of the invention will appear in the following description of the same, and the novel features thereof will be particularly pointed out in the claims.

In this instance I have illustrated the application of my invention to one well-known form 20 of type-writer; but I do not limit my invention to its application to any particular type-writer, but reserve my right to vary the construction herein shown and described in any manner and 25 to any extent necessary to adapt the same for use in connection with other forms of type-writers.

Referring to the drawings, Figure 1 is a plan 30 of a type-writer provided with my improved inking mechanism. Fig. 2 is a substantially 35 vertical section of the principal elements involved presented upon an enlarged scale. Fig. 3 is a side elevation of the principal elements in a modified form, and Fig. 4 is a plan of an 40 inking-disk.

Like letters indicate like parts in all the 45 figures.

A represents the impression-cylinder or platen of a type-writer of that class in which 50 said cylinder or platen is mounted in a pivoted frame-work, B, together with a guide-roll, C, rest D, and other well-known adjuncts for retaining the paper to be printed against the cylinder or platen, these parts being capable of a longitudinal movement along a supporting-rod, E, by means of suitable pawl-and-ratchet feed mechanism operated by the keys.

F represents the top plate of the machine, having the usual opening therein, on the margin of which are mounted the type-levers G, which are adapted to be operated by rods G',

connected in any suitable usual manner with the key.

Upon any suitable part of the top F, (at its front portion in this instance,) I mount a 55 bracket, H, and in order that it may be adjustable to and from the printing-point on the platen—that is, the point where the type comes in contact therewith—I slot the arm of the bracket, so that its attaching-screws H' may 60 be loosened and the bracket moved bodily, as desired. The inner end of the bracket is apertured to receive a collar or hollow shaft, I, on which is mounted a pinion, J, the collar or shaft being provided on the under side of 65 the bracket with a flange, I'. The bore of the hollow shaft is tapered to receive the tapered shank or stud K of a disk, L, so that said disk may be maintained in operative position by merely the friction of its stud K 70 within the hollow shaft, and so that the same may be easily removed and inserted, for a purpose hereinafter described.

M represents a rack-bar, which is secured to the under surface of the side rails of the frame 75 B adjustably by means of slots B' therein, in order that when the bracket is moved in or out the rack-bar may also be moved to maintain its connection with the pinion in all of its adjustments. When the bracket H is sup- 80 ported at either side of the top, the adjustable attachment of the rack-bar is not necessary, as the adjustment of the bracket will in that case be in line with the rack-bar, and the pinion J will remain in mesh therewith. 85

Between the flange I' of the collar or shaft I and the disk L, I insert a disk, N, of any suitable fabric or material which is adapted to yield or capable of yielding a color or ink when 90 it is forced against the paper to be printed by the printing character employed. The disk N may be made of silk, linen, or other cloth, paper, leather, or any other material capable of performing the desired function. For cheapness I prefer to employ paper saturated with 95 any of the well-known preparations of aniline or other suitable inks. I do not, however, broadly claim such disk.

In Fig. 1 the inner end of the bracket is enlarged to a disk shape, having an aperture, H², 100 through or into which the type G² passes or enters when making an impression. The ap-

erture H^2 is elongated to permit of the before-mentioned adjustment.

- As thus far described it will be seen that while in the ordinary operation of a type-writer of this class the carriage or frame B of the impression - cylinder or platen and the parts mounted thereon travel from side to side of the machine, the rack-bar M, meshing with the pinion J, will cause the hollow shaft I and disk L, together with the paper or inking material secured between the same, to rotate, so that a new surface is exposed after each one or more impressions thereon. The bracket and inking devices being supported upon the top of the machine, while the rack-bar is supported upon the pivoted frame, permits of an elevation of said frame for the purpose of inspecting the work, as is necessary in this class of machines.
- The advantages secured by rendering the bracket and rack-bar adjustable are now apparent, in that, supposing the adjustment to be such as to bring the type in contact with the inking-disk near its periphery, a slight adjustment of the bracket and rack inwardly will bring the type in contact with the disk nearer its center, and this being repeated, each disk is rendered serviceable for a longer period of time than if the parts were not rendered adjustable. This advantage resulting from the adjustment is a feature of my invention to which I do not limit it, as, by reason of the excessive cheapness of the inking-disks, the adjustable feature may be dispensed with.
- Where exceedingly light material is employed in the inking-disks I may provide in the under surface of the end of the bracket a groove, O, or other form of construction which shall serve to support the edges of the disk and yet permit of its rotation to present new surfaces for use.
- In Fig. 3 I have illustrated a modification, wherein the disk form of the bracket is discarded, by reason of the fact that the disk N, which holds, supplies, or acts as the inking material, is of sufficient substance and rigidity to maintain its form without the aid of external supports. As an example of such a disk I may mention a close-textured absorbent paper. The disk N is centrally apertured, as at N', to permit the passage therethrough of the stud K, in order that it may be secured in operative position by removing the stud and the disk L from the hollow shaft and returning them to position after the disk has been placed against the flange of the shaft—an operation which is readily performed by raising the

frame upon its pivot, as when inspecting work.

The disk employed may be coated instead of saturated with any suitable ink.

I am aware that fixed inking-pads over which printing characters are moved and subsequently passed through an opening in said fixed pad to make an impression have heretofore been employed in type-writers; but such pads have not been movable after each impression to present new inking-surfaces, nor have said pads been provided with an aperture by which they are adapted to be mounted on a rotary device for presenting new inking-surfaces. The well-known inking-ribbons have heretofore been mounted to be moved longitudinally after each impression of the type thereon; but such construction requires more space, more complicated mechanism, is less convenient and tidy, and more costly than my mechanism for supporting and rotating the disk.

I do not claim, broadly, the combination, with the platen of a type-writing machine, of a rotatable ink-disk interposed between the platen and type.

Having described my invention and its operation, what I claim is—

1. The combination, with the platen and the type of a type-writing machine, of a rotatable inking-disk removably supported between the type and the platen, substantially as specified.

2. In an inking apparatus for type-writing machines, the combination of a centrally-apertured absorbent ink-disk with a disk-supporting stud having a pinion, a rack, and a hollow shaft, whereby the disk may be supported in operative position and rotated, substantially as specified.

3. The combination of an apertured ink-disk, a hollow shaft, a disk provided with a stud inserted in the shaft, a pinion rigidly mounted upon the shaft, a supporting-bracket mounted on a fixed part of a type-writing machine, and a rack-bar mounted on a moving part of the same, substantially as specified.

4. The combination of the bracket H, provided with the slots H' H'', the hollow shaft I, provided with the flanges I' and pinion J, the tapered lug K and disk L, the disk N, the rack-bar M, and the slotted frame B, substantially as specified.

In testimony whereof I affix my signature in presence of two witnesses.

CHARLES SPIRO.
